LAMP CAP FOR LUMINESCENT TUBES OR
FLUORESCENT LAMPSJohn Liston, Cleveland, Ohio, assignor to Novelty
Lighting Corporation, Cleveland, Ohio

Application December 29, 1938, Serial No. 248,261

2 Claims. (Cl. 240—6)

This invention concerns improvements in, or relating to end caps for luminescent or fluorescent tubes or lamps.

An object of the invention is to provide a lamp cap which can be easily removed or replaced in exact position on the supporting bracket, thus allowing a burned out tube or lamp to be replaced by a new one without requiring readjustment of the cap when replaced.

10 A further object of the invention is to provide an instrumentality for accomplishing the above objects, which is simple in structure and use, efficient in operation, and economical to manufacture.

15 The invention and its aims and objects will be clearly understood from the following description, taken in connection with the accompanying drawing, of one embodiment of the invention herein given for illustrative purposes, the true scope of the invention being more fully pointed out in the appended claims.

In the drawing:

Figure 1 is an end elevation of the cap mounted on a conventional bracket.

20 Figure 2 is a side elevation of the cap, shown in Figure 1, the luminescent tube or fluorescent lamp is shown fragmentary.

Figure 3 is a side elevational view of the cap alone, shown in Figure 2, turned through 90° to show the flanges thereof, with indentations in each flange, and also a positioning rib in the interior of the cap.

25 Figure 4 is a side elevation of another embodiment of a cap, showing by way of example, the cap structure used when the supporting brackets are placed back to back, the luminescent tubes or fluorescent lamps are shown fragmentary.

Figure 5 is a side elevational view of the cap alone as shown in Figure 4, turned through 90° to show the indentations in each flange, also the position of the positioning rib therein.

30 Similar reference numerals indicate the same parts throughout the several views.

Referring to the drawing, the lamp cap 10 comprises a part encircling body 11 of suitable geometrical configuration, corrugated or otherwise, as shown at 12, having two longitudinally extending flanges 13 and 14 bent outwardly as at 15 and 16.

35 Each flange is provided with an indentation as shown at 17 and 18.

One end of the lamp cap is closed with a plate

39. It will be noted, see Figure 1, at 20 and 21, that the body portion of the lamp cap is free from

attachment with the plate for a short distance at each side to allow the body portion to spread and contract slightly to accommodate brackets that might vary from the standard specification in manufacturing. This freedom from attachment of the encircling body from the plate also provides a means to permit clamping of the lamp cap on the bracket through the interaction of the flanges with the bracket through the inherent resiliency of the metal constituting the cap.

40 The indentations in the similarly characterized flanges are so placed, that when the cap is slipped on the bracket or fixture, the bracket is held in contact with the inner surface 22 of the plate. The construction of the flanges and the position of the indentations in the flanges relative to the bracket dually function to hold the cap in clamped relation with the bracket, and at the same time prevents endwise movement of the cap relative to the bracket.

45 The rib 23 in the cap is provided to position the cap relative to the bracket and the luminescent or fluorescent tube or lamp, so that the cap per se will permit a circulation of air around that portion of the tube or lamp partly encircled thereby so that the heat storing zone created by the cap becomes a heat yielding zone. The forward end 24 of the rib is inclined off to a bevel-angle as at 25 so that the rib will easily ride up and into place on the bracket. The cap 50 is of a length sufficient to obscure the filament 26 in the tube or lamp as shown in Figure 2.

55 In the structure shown in Figures 4 and 5, the double cap 27 is provided with a positioning rib 28 having its ends 29 and 30 inclined off to a bevel-angle as at 31 and 32 so that the rib will easily ride up and into place on the bracket. The similar characterized flanges 33 and 34 are provided with indentations 35, 36 and 37 and 38, see indentations in flanges in Figure 5. The indentations are provided to properly position the cap in relation to the brackets, when the brackets are placed back to back as shown in Figure 4. The conventional brackets are shown in Figures 1, 2 and 4 at 39 and are all of the same general configuration and construction.

60 It will be understood that the caps are always of sufficient length to obscure the filament in the lamp or tube so that the light will be uniform throughout the length of the tube beyond the cap.

65 The caps may be embellished to bring them into conformity with the principles of esthetics in the lighting fixture art.

70 It will be understood that the cap shown in

Figure 1 and in Figure 2 is interchangeable from left to right and vice versa.

The luminescent tubes or fluorescent lamps are shown fragmentary at 40 in Figures 2 and 4.

5 The luminescent tubes or fluorescent lamps and fixtures in or on which the same is mounted, are of standard construction and form no part of the present invention.

It is believed that a résumé of the operation 10 of the cap is unnecessary.

Although the foregoing description is necessarily of a detailed character, in order to completely set forth the invention, it is to be understood that the specific terminology is not intended 15 to be restrictive or confining, and it is to be further understood that various rearrangements of parts and modification of structural detail may be resorted to without departing from the scope or spirit of the invention herein claimed.

20 What I claim as new and desire to secure by Letters Patent of the United States is:

1. In combination with a supporting bracket and a luminescent lamp, a cap comprising a part 25 enclosing body portion terminating in symmetrically aligned flanges having indentations formed therein at a predetermined location relative to

the supporting bracket, an end fixed in an end of the aforesaid enclosing body portion, and having opposite portions of the enclosing body portion adjacent the flanges free from attachment with the fixed end portion to permit outward yielding of the flanges when the cap is slipped endwise over the bracket, and a positioning rib fixed in the interior of the cap and extending into the body portion from the fixed end in the cap, and adapted to maintain the cap in spaced relationship with the bracket and the lamp.

2. In combination with supporting brackets and luminescent lamps, a cap comprising a part encircling body terminating in aligned flanges having spaced indentations formed in each 15 flange, a fixed positioning rib in the part encircling body intermediate the length thereof, the positioning rib adapted to position the cap relative to the brackets, the indentations formed in the flanges adapted to prevent movement of the 20 cap when the cap is mounted on the brackets, the laterally extending portions of the cap beyond the indentations being free from longitudinal support.

JOHN LISTON. 25
